CLEANING MATERIAL FEEDER FOR
WASHING MACHINESEdward C. Chandler, Cleveland, and Homer
Delamatter, Cleveland Heights, Ohio; said
Delamatter assignor to said Chandler

Application October 4, 1932, Serial No. 636,248

2 Claims. (Cl. 141—9)

This invention relates to devices for feeding cleaning material in washing machines of the spray type. Devices of this kind usually comprise a container, which holds a cleaning compound 5 in the form of a powder, and which is placed in the washing machine in such position that part of the spray can enter the container and dissolve the compound, and then flow into the machine, thus charging the wash water with cleansing material.

Heretofore, a device of this nature has embodied a container into which the powdered material has been placed and which has been provided with a water inlet opening at the top and 15 discharge openings in the bottom thereof. Thus the water trickled through the powder and gradually dissolved the same. We have found however, that when the machine is stopped, the water drains entirely from the container and the powder 20 becomes a hardened mass. Then when the machine is started, an interval of time approximating one-half hour is required before the hardened mass will be dissolved to the point where the wash water is being charged at the required 25 rate. We have also found that considerable difficulty has been experienced in providing the proper arrangement of the discharge openings for if they are too large the material is wasted, while if they are too small, the solution will not 30 flow at the required rate.

An object of our invention therefore is to provide a container which overcomes the objections enumerated and which can still be placed as a unit in the washing machine, and which will operate in a satisfactory manner by water which flows from the spray.

In the drawing, the figure is a side elevation, partly in section, of a device embodying our invention. In such illustration, we have shown a 40 container which is preferably cylindrical in shape and which has a side wall 10 and a bottom wall 11. A cover 12 may be hinged to the container at 13 and held in place by a spring latch 14. The container preferably has a partition 15 which 45 divides it into an inner compartment 16 in which the cleaning material is placed, and an outer compartment 17 which co-operates with the inner compartment to provide a tortuous path for the flow of the cleaning solution. To this end 50 the water inlet is indicated as an opening 20 in the center of the cover, while discharge openings are shown at 21 in the upper region of the wall 10 and below the top of the partition. The openings are spaced substantially equidistantly from 55 the bottom of the container, while additional

openings are shown at 22 in the partition 15 and preferably in the lower region thereof.

Thus, water entering through the openings 20 will enter the compartment 16, dissolve the cleaning material, flow outwardly through the opening 22, and thence upwardly in the compartment 17 and out through the openings 21. This arrangement thus provides a reservoir of dissolved material within the container so that the device is always available for immediate use. By moving the water in a tortuous path within the container, the concentration of the solution may be maintained at a uniform rate. Furthermore, by having the discharge openings below the top of the partition, the water is forced to trickle downwardly through the material and thus to effect a dissolution in a satisfactory manner.

Since the cleaning material is submerged within the water, it is desirable to provide some means for indicating the amount of undissolved material 75 within the container. To this end, we have shown a flat metallic member 30 which will sink in the water but which will bear against the top of the top of the undissolved material and be suspended thereby. A stem 31 projects upwardly from the part 30 through an opening in the cover, and thus provides a visible indicator for the amount of material in the container.

From the foregoing description, it will be apparent that we have provided a cleaning material 85 feeding device, which will now allow complete drainage of the container whenever the washing machine is stopped, and that we have provided an arrangement by means of which a visible indication of the amount of undissolved material 90 within the container is provided at all times.

We claim:

1. A device for dissolving cleaning material comprising a liquid container, an impervious partition therein, providing an inner and an outer compartment, a closure having a water inlet opening above the inner compartment, the outer compartment having a discharge opening through the container wall adjacent the upper portion thereof, and the partition having a plurality of passageways therein located only adjacent the lower end thereof but spaced slightly above the bottom, whereby the dissolved material flows from the inner to the outer compartment, thence upwardly and is discharged through the opening 100 in the container.

2. A device for dissolving cleaning material comprising a container having a partition therein forming two compartments, dividing it into a cleaning material storage compartment and a 110

solution storage compartment, means for introducing water in a downward direction into the material compartment, said partition having a plurality of passageways therein located only adjacent the lower end thereof but spaced slightly above the bottom, said partition being impervious above the passageways, said container having a discharge passageway extending from the solu-

tion compartment, and said discharge passageway being disposed near the top of the partition, whereby the two compartments are maintained substantially filled at all times with solution, and the container being impervious below the discharge opening. 80
